POWER TAKE-OFF

Clarence I. Bohmer, Columbus, Ohio, and Chris Gerst, Detroit, Mich., assignors to The Jaeger Machine Company, Columbus, Ohio, a corporation of Ohio

Application April 26, 1941, Serial No. 390,610

10 Claims. (Cl. 180—53)

Our invention relates to a power take-off. It has to do, more particularly, with a power take-off for use on a truck mixer where the power to drive the mixing drum is taken from the truck engine, although it is not necessarily limited thereto.

At the present time, it is customary with one type of truck mixer to take the power for driving the rotatable drum from the truck engine itself by associating a power take-off unit with the truck drive shaft which is split into front and rear sections. However, this prior art power take-off is possessed of certain disadvantages. It has usually included two jaw clutches, one for connecting the front section of the drive shaft to the rear section thereof to drive the rear wheels of the truck and the other for connecting the front section of the drive shaft to the transmission for rotating the mixing drum. With this type of prior art power take-off, when the truck is moving along it is impossible to engage the jaw clutch which controls rotation of the mixing drum. It is necessary to stop the truck, throw the main truck transmission in neutral and engage this clutch before the mixing drum can be rotated. The power take-off usually drives the transmission for rotating the mixing drum by means of a chain and sprocket drive. Prior art power take-off units of this general type are provided with an idler for taking up the slack in the chain. This idler causes considerable wear on the chain and is not completely effective. Prior art power take-offs are also possessed of other disadvantages.

One of the objects of our invention is to provide a simple, efficient and sturdy power take-off unit of the type indicated.

Another object of our invention is to provide a power take-off unit which is adapted to be associated with the split drive shaft of a truck mixer and which may be operated to drive the truck or drive the mixing drum independently of each other or simultaneously.

Another object of our invention is to provide a power take-off of the type indicated for a truck mixer which is of such a nature that it may be operated to drive the mixing drum even while the truck is moving along.

Another object of our invention is to provide a power take-off unit of the type indicated which drives the transmission for rotating the mixing drum by means of a chain and sprocket drive and which is provided with means for adjusting the tension of the chain without the use of an idler, and resulting wear to the chain, such means being very effective to keep the chain in the proper condition.

In its preferred form, our invention contemplates the provision of a power take-off unit which is associated with the drive shaft of a truck mixer,

the shaft being split adjacent the end into forward and rear sections. This power take-off drives a transmission disposed above it and adjacent the mixing drum, the transmission driving the mixing drum. The power take-off drives the transmission for rotating the mixing drum by means of a chain and sprocket drive which extends upwardly from the power unit to the transmission. To properly tension the chain, the entire power take-off unit is pivotally mounted on the drive shaft so that the end which carries the sprocket of the chain drive can be swung vertically. Means is provided for accomplishing this vertical adjustment and holding the unit in its adjusted position. The power take-off embodies a jaw clutch for connecting the two sections of the drive shaft together. However, it is provided with a multiple disk clutch for connecting the front section of the drive shaft to the chain and sprocket drive for the mixing drum transmission. With this arrangement, it is possible to engage the clutch for rotating the mixing drum even while the truck is in motion.

The preferred embodiment of our invention is illustrated in the accompanying drawings wherein similar characters of reference designate corresponding parts and wherein:

Figure 1 is a side elevational view illustrating how our power take-off may be associated with a truck mixer.

Figure 1a is a similar view of a portion of a truck mixer showing our unit associated with a different type of truck.

Figure 2 is a view, partly in end elevation and partly in transverse section, illustrating our unit on the truck mixer.

Figure 3 is a rear view, but partly in vertical section, of our power take-off unit.

Figure 4 is a horizontal sectional view taken through our power take-off.

Figure 5 is a similar view but showing a modification of our power take-off unit.

With reference to the drawings, and particularly to Figure 1, we have shown a truck mixer embodying a truck which has a main transmission 1, and a drive shaft 2. The drive shaft has our power take-off unit 3 associated therewith. This unit 3 drives the transmission 4 which controls rotation of the mixing drum 5. Our unit 3 will be described in detail hereinafter. The transmission 4 does not form a part of the present invention and is substantially the same as that disclosed in the co-pending application of Jaeger et al., Serial No. 350,586, filed August 3, 1940 and directed to Truck mixer transmission control.

The drive shaft 2 of the truck is split into forward and rear sections and the unit 3 is located adjacent the split portion of the shaft. The unit 3 is illustrated best in Figures 2, 3 and 4. It is

carried by a transversely extending front plate 6 and a transversely extending rear plate 7 which are vertically disposed and are carried by the truck frame. The front section of the shaft 2 is connected by a suitable coupling 8 to a short shaft section 9 forming a part of the unit 3. The rear section of the shaft 2 has its forward end connected by means of a similar coupling to a short shaft section 11 which is in alignment with shaft section 9 and forms a part of unit 3. The two sections 9 and 11 have their inner ends 10 adjacent each other.

The shaft section 9 is rotatably disposed within a ball bearing 12 disposed in aligning openings formed in the plate 6 and in the wall of the housing 13 of the unit 3. The inner end of the shaft section 9 has keyed thereon a gear 14. This gear 14 has a hub 15 which surrounds the shaft section 9 and which is rotatably disposed within a ball bearing 16 carried by a support 17 forming 15 part of the housing 13. Gear 14 has an exterior helical gear portion 18 and an interior straight gear portion 19. The shaft section 11 is rotatably mounted in a ball bearing structure 20 disposed in aligning openings formed in the plate 7 and the wall of the housing 13. This section 11 has an inner reduced end 21 which is rotatably mounted within gear 14 by means of a ball bearing 22. The shaft section 11 carries a clutch section 23 which is adapted to cooperate with gear 14. This section 23 is splined to the shaft section 11. It is provided with an exterior straight gear portion 24 which is adapted to slide into and interlock with the gear portion 19 of the gear 14. The clutch section 23 is moved axially 25 of the shaft section 11 by means of a yoke member 25 which extends into an annular groove 26 formed in member 23. The yoke member 25 has its outer end rigidly secured to a pin or rod 27, as at 28. The rod 27 is reciprocably mounted in bearing portions 29 formed on housing 13. The rod may be reciprocated by a suitable control member 30 extending to the cab of the truck. A spring-pressed ball 27a fits into either of two 30 sockets in rod 27 to lock it in either of its positions, that is, engaged or disengaged. Thus, it will be apparent that a gear tooth type clutch is provided which may be actuated to connect the front section of the drive shaft 2 to the rear section thereof. As long as the front section of the drive shaft 2 is rotated by the truck engine, the gear 14 of the clutch will be rotated. However, the section 23 of the clutch will not rotate until it is engaged with the gear 14.

The gear 14 drives a drum 31 by means of the helical gear portion 18 which engages a similar gear portion 32 on the drum 31. The drum 31 forms a part of and encloses a disk type clutch. The drum 31 is mounted for relative rotation on a shaft 33 by means of ball bearings 34. The shaft 33 is rotatably mounted in ball bearings 35 and 36 carried by the housing 13. The drum 31 carries a plurality of clutch disks or rings 37 which have notches in their periphery that interfit with ribs 38 carried on the interior of the drum. Thus, the members 37 can move axially of member 31 but will rotate therewith. The shaft section 33 carries a hub member 33a which is keyed thereto and which carries disks or rings 39 which are similarly splined thereon. The members 37 fit between the members 39. A pin and spring structure 40 normally keeps the members 39 in spaced relationship. Ordinarily the members 37 and 39 are spaced from each other and, therefore, the drum 31 will

not drive the shaft section 33. However, in order to force the members 37 and 39 into frictional contact with each other, we provide an actuating plate unit 41 of a suitable type which is splined to the hub 33a. This plate unit 41 is moved axially of shaft 33 by means of a plurality of rocker members 42 which are pivoted, as at 43, to a collar member 44 keyed to the hub 33a. Members 42 are disposed at circumferentially spaced intervals and carry rollers 44a on each end thereof. One set of these rollers 44a engages a beveled surface 45 on unit 41. Between the rollers 44a and in engagement with both sets thereof is an actuating ring 46. This ring is provided with a groove 47 which is engaged by an actuating yoke 48. When the yoke 48 is moved in the proper direction it forces ring 46 against one set of rollers 44a and rocks members 42. Rollers 44a engaging the beveled surface 45 will force the unit 41 in the proper direction to force the disk members 37 and 39 in tight contact with each other. This will cause shaft 33 to be driven. The yoke is keyed on the lower end of a shaft 49 which extends upwardly through housing 13 (Figure 3) and which is rotated by means of a lever 50. The lever 50 may be actuated by suitable controls extending to the cab of the truck and to the rear of the truck.

Whenever the front section of the shaft 2 of the truck is driven by the truck engine, the drum 31 will be rotated. However, the shaft 33 will not be driven until the disk clutch is operated.

The shaft 33 extends through a slot 51 formed in the plate 7. It projects outwardly from the housing 13 and has a sprocket 52 keyed on the outer end thereof. This sprocket 52 drives a sprocket chain 53 (Figures 2 and 3) which extends upwardly and drives a sprocket 54 which is suitably connected to the input shaft of the transmission 4. The entire housing 13 is free to swing about the aligning shaft sections 9 and 11. The shaft 33 is disposed parallel to such sections and a substantial distance therefrom. The sprocket 54 is disposed at a point between shaft 33 and the sections 9 and 11, as shown in Figure 2. It will be apparent that by swinging the left hand end (Figures 2 and 3) of the housing 13 vertically, the tension on the chain 53 may be varied. To vertically adjust the housing 13 in this manner and hold it in adjusted position, we provide a yoke member 55 secured to the end of the housing. This yoke member has portions 56 engaging trunnions 57 projecting outwardly from a collar 58. The collar 58 is interiorly threaded and receives the vertically disposed screw 59. This screw 59 is suitably rotatably mounted in a housing 60 bolted on the truck frame intermediate the front and rear plates 6 and 7. The screw 59 is provided with a head 61 which may be engaged by a wrench so that it may be rotated. Rotating the screw 59 will swing the housing 13 vertically. Thus, the tension on the chain 53 may be adjusted easily and efficiently.

The power take-off unit just described may be operated to drive the truck or drive the mixing drum independently of each other or simultaneously. To drive the truck it is merely necessary to engage the gear tooth type clutch. To rotate the mixing drum it is merely necessary to actuate the disk clutch. The mixing drum may be actuated at any time that the drive shaft 2 is operated by the truck engine. It can be engaged without throwing the main truck mixer transmission 1 in neutral. It will also be apparent that we have

provided means for quickly and efficiently adjusting the tension of the chain which drives the mixing drum transmission 4. Furthermore, this means is of such a nature that it will eliminate excessive wear on the chain.

The power take-off unit previously described is particularly useful with trucks where the main transmission 1 is located ahead of the unit 3, as in Figure 1. However, some trucks, as indicated in Figure 1a, have the main truck transmission 1a located at the rear at a point which will be behind our unit 3a. In such instances, it is desirable that the power take-off 3a be of the type shown in Figure 5.

This unit is enclosed within a housing 13a as before. A shaft section 9a is rotatably mounted in the housing. The shaft section 9a is connected to the forward section of the drive shaft of the truck and also to the rear section thereof. In other words, the section 9a is a portion of the continuous drive shaft 2a (Figure 1a) of the truck. A drum 31a of a disk type clutch is rotatably mounted by means of a ball bearing 34a on the shaft 9a. This disk type clutch is practically the same as that previously described and need not be described in detail. It is actuated by means of a yoke 48a. When the clutch is engaged, it connects the drum 31a to the shaft section 9a for rotation therewith. The drum 31a has a gear portion 18a carried thereby which engages a gear portion 32a keyed on a shaft 33a rotatably mounted in the housing 13a in parallel relationship to the shaft section 9a. The shaft section 33a carries a sprocket 52a as before. The housing 13a is mounted for vertical swinging movement like the housing 13 and will swing about the axis of shaft section 9a.

In the operation of this power take-off unit, the shaft 2a will be rotated whenever the truck engine is operated. The drive to the wheels of the truck will be controlled by actuation of the main truck transmission 1a. Whenever the truck engine is in operation and it is desired to drive the mixing drum, the disk type clutch is actuated to drive the shaft 33a. Thus, with this power take-off, the mixing drum may be rotated when the truck is stationary or when it is moving. The disk clutch may be actuated to drive the mixing drum even when the truck is in motion.

It will be apparent from the above description that we have provided a power take-off unit having many advantages. Most of these advantages have been discussed but others will be apparent from the drawings and the following claims.

Having thus described our invention, what we claim is:

1. In combination with a truck having a main engine for moving it along, a drive shaft driven thereby, a driven unit mounted on said truck, means for driving said unit, a power take-off unit associated with said drive shaft for transmitting power from said shaft to said means for driving said first-named unit, said power take-off unit comprising shaft sections which form continuations of said drive shaft, one of said sections being driven by the main engine and the other being adapted to drive the wheels of the truck, a clutch interposed between said sections for selectively connecting or disconnecting them, a separate shaft section connected to said means for driving said driven unit, and a friction type clutch for

selectively connecting or disconnecting said last-named shaft and said driven shaft section.

2. A structure according to claim 1 wherein the friction clutch is of the multiple disk type.

3. A structure according to claim 1 wherein the means for driving said driven unit comprises a transmission which is driven by means of a chain and sprocket drive from said last-named shaft.

10 4. A structure according to claim 1 wherein the means for driving said driven unit comprises a transmission which is driven by means of a chain and sprocket drive from said last-named shaft, said power take-off unit being mounted for movement relative to said transmission to adjust the tension of said chain.

5. A structure according to claim 1 wherein the said last-named shaft is connected to the means for driving said driven unit by a chain and sprocket drive, said power take-off unit being movable to adjust the tension of said chain.

6. In combination with a truck having a main power unit and a drive shaft, a power take-off unit associated with said shaft, a unit adapted to be operated by said power take-off unit and disposed above said shaft, said power take-off unit being mounted for pivotal movement about the axis of said shaft, a separate shaft forming a part of said power take-off unit and being disposed parallel to said drive shaft, said separate shaft carrying a sprocket which drives a chain that operates said second-named unit, and means for adjusting said power take-off unit about said drive shaft.

7. A structure according to claim 6 wherein a clutch is provided for selectively connecting said drive shaft to said separate shaft.

8. A structure according to claim 6 wherein a clutch of the multiple disk type is provided for selectively connecting said drive shaft to said separate shaft.

9. In combination with a drive shaft, a power take-off unit associated with said shaft, a unit adapted to be operated by said power take-off unit and spaced from said shaft, said power take-off unit being mounted for pivotal movement about the axis of said shaft, a separate shaft forming a part of said power take-off unit and being disposed parallel to said drive shaft, a clutch associated with said drive shaft for selectively connecting it to said separate shaft, said separate shaft carrying a sprocket which drives a chain that operates said second-named unit, and means for retaining said power take-off unit in a selected position to which it is pivoted about said drive shaft.

10. In combination with a sectional drive shaft, a power take-off unit interposed between sections of said shaft, said power take-off unit comprising a pair of shaft sections axially aligned with each other and with the sections of the drive shaft, a jaw clutch for selectively connecting the adjacent ends of said pair of shaft sections together, an independent shaft section, a member freely rotatable on said independent shaft section, means for driving said member from one of said pair of shaft sections, and a disk-type clutch associated with said member for selectively connecting it to said independent shaft section.

CLARENCE I. BOHMER.
CHRIS GERST.
